[57] **CLAIM**

The ornamental design for a combined handle and escutcheon, as shown and described.

DESCRIPTION

FIG. 1 is a perspective view taken from the top, front and right side of a combined handle and escutcheon showing my new design;

FIG. 2 is a front elevational view thereof, the rear being the same as the front shown;

FIG. 3 is a left side elevational view thereof, the right side being a mirror image of the left side shown;

FIG. 4 is a top plan view thereof; and

FIG. 5 is a bottom plan view thereof.

FIG. 1

FIG. 2

FIG. 3

FIG. 4
